LOUD-SPEAKER MOTOR

Application filed September 4, 1928. Serial No. 303,878.

This invention relates to electromagnetic reproducers, and is particularly applicable to loud speakers such as are used in radio broadcast reception, although its application is not necessarily limited thereto.

One object of this invention is to provide an electrical sound reproducer adapted to be used in the output of conventional receivers whose armature or moving element is not limited in action by the pole pieces or other obstruction when strong currents are applied to the windings.

Another object is to provide a method by means of which, if so desired, all signals, speech, music, etc. are limited in volume to a predetermined maximum amount, regardless of strength in order that listeners will not be annoyed when tuning in, by extremely loud stations, accidentally or otherwise before the volume control is properly adjusted.

Another object is to limit disturbances, noise, atmospherics, etc. to this predetermined sound level.

Another object is to provide an efficient but inexpensive loud speaker driving motor which may be easily duplicated in quantities with great uniformity of electrical and acoustical characteristics.

A further object is to provide a driving unit for incorporating into a complete loud speaker and which may be built into radio broadcast receivers or readily attached to standard broadcast receivers.

Other objects and advantages of our invention will become apparent later in the specification.

As is well known in the art, standard electromagnetic telephone receivers, while very sensitive, cannot be supplied with more than a certain amount of signal energy without the diaphragm hitting the pole pieces of the magnets, making the music or speech practically unintelligible and distorted, causing what is often called "blasting" in the case of the reproduction of music. Many loud speakers of the past have used merely enlarged magnetic telephone receiver elements as the motivating unit to drive the sound reproducing diaphragm. Probably the most widely used driver for loud speakers in the

radio art at present is the so-called balanced armature type of unit which is subject to the same objection. Comparatively narrow energy level is required to be furnished to the unit, above which satisfactory reception may not be attained, even though undulatory currents of practically undistorted characteristics be furnished the driving unit. 55

Broadly speaking our invention contemplates the use of a forked armature so arranged that the movable tips can not strike any abutment within its operating range of movement. 60

Referring to the drawings, it will readily be appreciated that in the various forms our unit may be built, the vibrating armature is spaced apart from and cannot come in contact with pole pieces or other parts, regardless of the signal energy supplied the system, and the only limiting factors are those such as affecting the burning out of the magnet windings or saturation of the vibrating armature, design features which may be predetermined and set to suit the service for which the unit is intended. 70

At the same time the units shown may be designed to be sufficiently sensitive to respond to very weak impulses. Thus our invention provides a loud speaker driving unit for the usual type of output circuit by means of which satisfactory reproduction of sound may be obtained even though supplied with widely varying energy levels, as compared to units now in common use. 80

Fig. 1 is a side view of one form of our invention in which the energizing coils are mounted on the pole pieces of a permanent magnet core and the armature has two off set arms centrally pivoted between the coils. 85

Fig. 2 is an end view of the same. 90

Fig. 3 is a side view of another form similar to Fig. 1 but with the coils on or around the armature.

Fig. 4 is an end view of the same. 95

Fig. 5 is a side view of a form in which the forked armature is pivoted to one pole piece of the magnet and the coils are supported in place so that the armature tips can vibrate within them.

Fig. 6 is an end view of the same. 100

Fig. 7 is a side view of another form with a forked armature having its shank secured to one magnet pole and two coils on the other pole coacting with the movable tips 5 of the armature.

Fig. 8 is an end view of the same with its differentially wound coils.

Fig. 9 is a sectional view of another form having magnetizing coils in place of the permanent magnet and with an oscillating forked armature and a single energizing coil.

Fig. 10 is a diagrammatic view showing one form of output circuit with a reproducer according to our invention.

In the form shown in Figs. 1 and 2 the magnet 12 is provided with two pole pieces 13 each of which is preferably laminated to reduce eddy current losses and each of which has two tips 14, 14. The armature has a pivot shaft 15 with two arms 16, 16' set cross-wise so that their tips are respectively above and below the adjacent tips of the pole pieces. The armature is connected in any suitable manner for instance by means of a drive rod 25 or wire 17 to any suitable form of diaphragm or air vibrator 18. The coils 19 which are connected in the audio output circuit of the receiver (not shown) may be suitably mounted upon or around either the pole pieces of 30 the magnet or the armature. In Figs. 1 and 2 these coils are mounted on the tips 14 of the magnet pole pieces.

The construction shown in Figs. 3 and 4 is similar to that of Figs. 1 and 2 except that the coils 20 are mounted so as to surround the armature members instead of the pole pieces of the stationary magnet. In both forms of construction, however, it will be noted that the armature when it vibrates 40 can not come in contact with the pole pieces of the magnet and, therefore, there can be no blasting nor crashing sound even when an excessive current is applied to the circuit.

In the form shown in Figs. 5 and 6 the stationary magnet and its pole pieces are similar to the ones above described. The armature shaft 21 however in this case is mounted close to the pole pieces 22 and the armature is provided with two arms the tips 50 of which are located above and below respectively the tips of the pole piece 24. The pole pieces are shaped to most effectively coact with the armature. The coils 25 are supported at 26 and the armature tips extend through these coils.

In the form shown in Figs. 7 and 8 the pole pieces 30 support the coils 31, 32 and the armature 33 is supported on the other pole of the magnet and provided with two 60 branches or arms 34, 35. Two branches or forks 34, 35 are preferably connected together by cross piece 36 to which the drive rod or wire 37 is secured. The coils 31 and 32 are differentially wound so as to properly coact with the armature members.

In the construction shown in Fig. 9 the magnet 40 may be of the non-permanent type and provided with windings 41 for providing the necessary field strength. In this case the pole pieces 42 are suitably secured to the main part of the magnet. The magnetic armature has two tips 43 supported by a bar 44 also of magnetic material which passes through the energizing coil 45 and the tips of the armature forks are arranged close to the tips of the pole pieces 42 but in position so that they can not touch no matter what the vibration of the armature may be. The upper end of the armature may be adjusted by set screws 46 which are supported in a strap 47. 48 is the drive rod connected to the air vibrating member.

Fig. 10 shows a typical circuit arrangement for use with our invention. In this case the primary of the transformer 50 is connected in the plate circuit of the output tube 51 of the receiver and the secondary is connected by leads 52 to supply energy to actuate the armature of the motor 53 to drive the diaphragm 54.

While we have shown the loud speaker connected with the output tube through an output transformer, it is apparent that other conventional means can be employed, such as through a large condenser, the plate obtaining its voltage direct from the plate supply through a suitable choke coil. Or, the actuating coil may be designed to connect directly to the plate and power supply without an intervening transformer or filter.

It is expected, of course, that the physical laws obtaining for loud speaker motors, known to those skilled in developing these units, be applied in the design of our unit together with the output circuit for which it is intended. If transformer coupling is used from the output or power tube, it should have a primary impedance at very low audio frequencies, approximately equal to the internal impedance of the tube. The secondary 105 of the transformer should be equal to or "match" the impedance of the actuating coil system, and should be coupled to the primary in such a manner that practically equal efficiency of transfer obtains over the audio frequency spectrum. Likewise the mechanical dynamic impedance of the driving system should equal that of the driven diaphragm or other sound producing arrangement.

The volume obtainable before the limiting 120 action begins is determined by the distance the armature travels toward the field pole until further travel does not reduce the air gap. When the nearest edge of an armature tip is opposite an edge of a field pole further 125 armature travel does not materially reduce the air gap which is the principal part of the reluctance of the magnetic circuit. Consequently a very strong signal will give but little increase in volume over a weaker sig- 130

5   nal that is strong enough to place the armature at instants of full current amplitude, in the position of least reluctance. The slight difference in volume between two such signals would be due to the inertia of the
10   stronger carrying the armature slightly past this position. In no case can the armature come in contact with the field poles, and if the strong signal as delivered to the loud-speaker is free from distortion, and the loud speaker is correctly designed, as pleasing reproduction will result from very strong music or speech as from that of moderate intensity.

15   To obtain this result, the air gap should be such that the maximum working range of the armature is suitable for the services intended, i. e., home broadcast receiving as compared to a public address service; the armature must not saturate with the strongest signal the output tube is capable of delivering and the diaphragm must not "rattle" with the maximum volume that the air gap is set for.

20   With such a reproducer, interfering disturbances, atmospherics, etc., are limited in amplitude to that of the accompanying music or speech though initially many times stronger. Likewise the annoying effects of fading are partly done away with inasmuch as the amplifier may be adjusted for great sensitivity and the signal will be of practically constant volume as long as it does not fall below the level necessary for this volume requirement.

25   35 We claim:

40   1. A loud speaker motor comprising a magnetic core having pole pieces and coil windings and an armature supported at one end and having the other end forked and with tips disposed adjacent the pole pieces of the magnet.

45   2. A loud speaker motor comprising a magnetic core having pole pieces and coil windings and an armature supported at one end and having the other end forked and with tips disposed adjacent the pole pieces of the magnet and means for limiting the vibration of the armature.

50   3. A loud speaker unit having two armatures, a field magnet coacting therewith and means comprising differential windings for simultaneously increasing the flux density of one armature while decreasing the flux density in the other armature.
